UNITED STATES PATENT OFFICE.

JOHN W. WATKINS AND JAMES S. COCHRAN, OF PHILADELPHIA,
PENNSYLVANIA; SAID WATKINS ASSIGNOR TO SAID COCHRAN.

MACHINE FOR DELINTING COTTON-SEED.

SPECIFICATION forming part of Letters Patent No. 430,496, dated June 17, 1890.

Application filed December 9, 1889. Serial No. 333,115. (No model.)

To all whom it may concern:

Be it known that we, JOHN W. WATKINS and JAMES S. COCHRAN, citizens of the United States, residing in the city and county of Philadelphia, State of Pennsylvania, have invented a new and useful Improvement in Machines for Delinting Cotton-Seed, which improvement is fully set forth in the following specification and accompanying drawings.

10 Our invention consists of improvements in machines for cleaning or delinting cotton-seed, the several features thereof being hereinafter fully set forth, and definitely pointed out in the claims.

15 Figure 1 represents a partial side elevation and partial vertical section of two machines for cleaning or delinting cotton-seed, showing our invention. Fig. 2 represents a top or plan view of one of the machines and connected parts. Fig. 3 represents a side elevation of the machine parts shown in Fig. 2, showing portions of the same in section. Fig. 4 represents a side elevation of the brush of the machine, part of the same being 25 separated. Fig. 5 shows a side elevation of a connected series of machines.

Similar letters of reference indicate corresponding parts in the several figures.

Referring to the drawings, A designates the 30 frame of the machine, and B designates a conical casing, which is mounted therein and having within the same the brush C, the latter consisting of a cone-shaped backing D, with brush material thereon, said material being 35 formed of a strip E, of leather or other suitable material, with wires or teeth F attached thereto, the strip being wrapped around the backing and fastened by a wire or cord G, which is wound spirally around the strip in 40 the space between the wires or teeth thereof, and secured at its ends by staples G', as shown in Fig. 4, which are driven through the strip into the backing and embrace the wire, the strip thus being most firmly bound to the 45 backing and securely held thereon.

H designates a feed or supply box, which is located adjacent to the casing B, and into the same dips the endless conveyer J, which is supported on a suitable frame K, and is

operated by a wheel or pulley K', (shown in 50 dotted lines, Figs. 2 and 3,) to which power is suitably communicated. The buckets L of the conveyer discharge into a chute M, which is located above the casing B and communicates with feed-openings N in the top of said 55 casing, whereby the latter may be supplied with seed to be cleaned or delinted.

The casing B has a hinged door P, whereby access is had to the interior of said casing and the brush, it being noticed that the inner surface of the casing is clad with brush material Q, preferably wire.

The brush C is rotated in any suitable manner, it being noticed that in the drawings its shaft is mounted on the frame A, and 60 carries a pulley C' for rotating said brush.

When the machine is in operation, the seed is carried from the box H by the conveyer J to the chute or receptacle M, and thus directed through the openings N into the casing B, where it is subjected to the brush therein, and thus cleaned or delinted. Below the brush is a box R, within which is a chute or deflector S, the said box being in communication with the open bottom of the casing 70 B. The box R opens into a seed box or receiver T, into which dips the endless conveyer U of any preferred construction, and consisting in this instance of buckets R', attached to flexible side supports R², passing 80 over rollers, pulleys, or sprocket-wheels T', and said buckets discharge into an elevated conveyer V. The box R has connected with it a funnel W, which leads to a blower or exhaust-fan X, from which leads a discharge 85 pipe Y. It will now be seen that as the seed cleaned or delinted leaves the brush and falls through the opening in the bottom of the casing it is directed by the chute S into the box R and drops into the receiver T, after 90 which it is taken up by the conveyer U and deposited into the conveyer V, said conveyer V, which may be of any preferred construction and operated as may be desired, being shown as composed of flexible side supports 95 V², passing around pulleys, rollers, or sprocket-wheels V³ and carrying floats V⁴. Simultaneously therewith the blower or fan X

draws the lint from the casing B through the box R and funnel W, and directs the same into the pipe Y, by which it may be discharged elsewhere.

5 It is important to employ large volumes of air in order to effect the proper discharge of the lint from the casing. For this purpose we form in the top of the casing inlets Z, in the side of the funnel W an inlet Z', and in the side of the box R an inlet Z², so that air may be drawn into and through said casing, box, and funnel, and thus effectively carry away the lint through the blower or fan. The vent or inlet Z' in funnel W is provided with a 15 movable cover Z³, and may be opened or closed to compensate for variations in barometric pressure. When the pressure is high, the said vent is opened to prevent upward suction of the seed with the lint, and when the 20 pressure is low the vent or inlet is closed to establish sufficient suction to raise the lint. The inlets are preferably guarded by gauze or netting to prevent the entrance of improper matter into the casing B. The fan Z³, Fig. 1, 25 aids in blowing the lint from the seed passing over the chute S by directing a blast thereon through the opening in the bottom of casing B.

In Fig. 1 we show a duplication of the 30 machine, the seed passing through first one machine and then the other, and in Fig. 5 a triplication of the same.

When a battery of three machines is used, the seed is placed in the first two machines 35 and delinted, and the cleaned seed therefrom unitedly delivered into the third machine by being deposited on the conveyer V from said first and second machines, and from said conveyer V being carried by chute V', leading 40 to the seed-receiving-box II of the third machine, where the delinted seed is further subjected to a cleaning action. If desired, the seed may be placed in the first machine and successively cleaned in the remaining machines composing the battery.

In practice the brush of the first machine is somewhat coarser than those of the other machines of the series or team, so that the 45 cleaning or delinting may be gradually accomplished.

Having thus described our invention, what

we claim as new, and desire to secure by Letters Patent, is—

1. A brush for delinting or cleaning cotton-seed, composed of a backing or body having 55 wound thereon a strip of card or brush clothing composed of a backing provided with wires or teeth inserted therein, and having said strip bound to the backing by a cord or wire wound upon the same and lying between 60 the teeth, substantially as described.

2. A machine for delinting or cleaning cotton-seed, consisting of a casing with a brush on the inner surface thereof and a revolving brush within the same, said revolving brush 65 consisting of a body, a strip of toothed material wound thereon, and a binding wire or cord wound upon said strip and secured to said body, substantially as described.

3. A machine for delinting or cleaning cotton-seed, having a revolving brush consisting of a conical body, a strip of toothed material wound thereon, and a binding wire or cord wound upon said strip and secured to said body, and a casing conforming to said brush 75 and having an inner brush-surface, substantially as described.

4. An organized machine for delinting or cleaning cotton-seed, having a casing with a brush therein, a box for receiving the cleansed 80 seed, and a funnel or pipe leading from said box to a blower or fan, said casing, box, and funnel having air-inlets, substantially as described.

5. A battery of machines for delinting or 85 cleaning cotton-seed, each having a casing with a brush on the inner surface thereof and a revolving brush within the same, a seed-receiving box, and a suction funnel or pipe leading from said box, said casing, box, 90 and funnel having air-inlets, an elevator leading from the seed-discharge box of one machine, and a conveyer receiving the seed from said elevator and leading to a feed-opening of another machine, substantially as de- 95 scribed.

JOHN W. WATKINS.
JAMES S. COCHRAN.
